UNITED STATES PATENT OFFICE.

HOWARD G. SHORTT, OF CARTHAGE, NEW YORK, ASSIGNOR OF ONE-THIRD TO JOHN G. JONES
AND ONE-THIRD TO EDWARD G. SHORTT, OF CARTHAGE, NEW YORK.

VACUUM-ACTUATED SCREEN.

No. 896,473.

Specification of Letters Patent.

Patented Aug. 18, 1908.

Application filed December 19, 1907. Serial No. 407,207.

To all whom it may concern:

Be it known that I, HOWARD G. SHORTT, a citizen of the United States, residing at Carthage, in the county of Jefferson and State of New York, have invented certain new and useful Improvements in Vacuum-Actuated Screens; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in screens for treating wood pulp or other material and consists in the provision of means whereby a vacuum of force may be applied to operate a diaphragm, thereby imparting a quick upstroke to the screen resulting in the freeing of the slots in the plates of stock or any foreign matter which may become lodged therein. Heretofore it has been the practice in screens for this purpose to connect the diaphragm direct with a cam, whereas by the apparatus involved in my invention the operation of the apparatus may be greatly accelerated, thereby greatly increasing the capacity of the screen.

The invention comprises various details of construction and combinations and arrangements of parts which will be hereinafter fully described and then specifically defined in the appended claims.

My invention is illustrated in the accompanying drawings, in which:—

Figure 1 is a vertical sectional view through the screen. Fig. 2 is a vertical sectional view showing the piston at its extreme lower end of stroke. Fig. 3 is a vertical sectional view through the pneumatic piston on its upstroke. Fig. 4 is an enlarged sectional view of the relief valve showing a modification in which a spring is added to the valve, if desired. Fig. 5 is a top plan sectional view taken on line A—A of Fig. 1, showing the stock outlet ports from the top of the diaphragm. Fig. 6 is a vertical sectional view on line B—B of Fig. 5. Fig. 7 is a side elevation, partly in section showing the diaphragm at its up position.

Reference now being had to the details of the drawings by letter, A designates a stand-

ard upon which the screen box B is mounted, having a suitable screen C mounted therein and C' designates a pipe through which the stock is fed into the box and upon said screen.

D designates a diaphragm which is mounted within a screen box below the screen, there being two of said diaphragms, one upon either side of the transverse center of the box as illustrated in Fig. 5 of the drawings and intermediate the diaphragms are formed the ports E leading into the delivery box E', shown clearly in Figs. 1, 5 and 6 of the drawings. Fixed to each diaphragm is a plate D² having a stem D³ projecting from the face thereof, said stem being mounted in a guide-way D⁴ positioned centrally in the opening D⁵ which is formed in the casting F secured to the bottom of the screen box, as clearly illustrated in Figs. 1 and 7 of the drawings. Said casting F has securely fastened thereto a pneumatic cylinder G in which a power piston H is adapted to have a reciprocating movement and H' is a pitman connected to a pin h upon the piston H and its other end to a strap H² mounted upon the eccentric I which is keyed to the driving shaft I'. It will be noted that there are two eccentrics connected to separate pistons, one for operating the diaphragm, only one, however, of the pneumatic cylinders being illustrated in Fig. 1 of the drawings, although a portion of the second piston and eccentric are illustrated in elevation in said figure.

A coiled spring J is mounted about the stem D³ and the guide D⁴, in which said stem reciprocates, and one end of the spring bears against the plate D² upon the diaphragm and its other end against a portion of the casting D⁵ in which said stem is mounted, the purpose of said spring being to return the diaphragm to its normal position after having been drawn downward by a suction force, due to the formation of a vacuum in the cylinder G and the passageway leading therefrom to the under side of the diaphragm. Said cylinder G has ports g formed therein to allow air to enter the cylinder to break the vacuum and allow the diaphragm to be returned to its normal position by the action of the spring bearing against the same. A relief port K leads from the upper portion of said cylinder to a valve regulated port N in which a valve N' is mounted, thereby allowing the air above the piston H to make exit to the atmosphere and avoid any unnecessary compression.

of the air in the cylinder or passageway leading therefrom to the space below the diaphragm. If, however, compression is desired to perform the duties of said spring J, a 5 spring L, shown in Fig. 4 of the drawings, may be utilized, which spring L is placed about the stem of the valve N', thus retaining the pressure within the cylinder G equal to the weight or strength of said spring L

10 Mounted within the flow box M is a dam M' over which, when the screen stock rises to the stock level upon the diaphragm, will run over into the discharge opening Q, shown in Figs. 5 and 6 of the drawings, and from 15 which it may be conveyed to any suitable location.

In operation, the stock being fed through the screen box runs through the slots in the screen and, at each rotary movement of the 20 driving shaft I, a diaphragm is drawn down as illustrated in Fig. 1 by a suction force due to the formation of a vacuum within the cylinder as the piston moves outward. When the piston H reaches the position 25 shown in Fig. 2 of the drawings so as to open the ports g in the wall thereof, air rushing into the portion of the cylinder above the piston will cause the vacuum formed therein to be broken and the diaphragm will move 30 quickly upward, thereby clearing the slots of the screen of any stock or foreign matter which may become lodged therein. Upon the return upper or inner throw of the piston H, when the latter closes the ports g 35 and assuming the position shown in Fig. 3 of the drawings, any air which may be trapped in the space above the piston will make exit through the relief port K and the valve-regulated duct N to the atmosphere to 40 avoid compression of the air in the cylinder and space leading therefrom to the diaphragm. Upon the next outer throw of the piston, the same operation is repeated. The screen stock passing through the port E into 45 the flow box will seek its level in the screen box and run into the flow box M and run over the dam at the end thereof to the discharge opening from which it may be conveyed to any suitable location.

50 By the provision of an apparatus as shown and described, it will be understood that a series of rapid strokes may be imparted to the pistons, causing quick vibratory movements to be imparted to the diaphragm 55 whereby any foreign matter lodging in the slots of the screen may be freed therefrom and, as the diaphragms are entirely separate from the pistons, it will be impossible to break the screen plates by their becoming 60 plugged as is commonly a trouble in screens having direct connection with cam actuated mechanism. When the diaphragm has direct connection with a cam eccentric actuated mechanism, the vacuum created above the 65 diaphragm, it has been found, will invariably

collapse the screen plate. In the event of any leakage through the diaphragm, the water will pass through the casting, from which it will be expelled through the relief ports by the reciprocating movement of the 70 piston in said cylinder.

What I claim to be new is:—

1. A pulp screening apparatus comprising a stock receptacle with the screen therein, a diaphragm mounted beneath the screen, a 75 pneumatic cylinder having a free communicating space intermediate the same and said diaphragm, a piston mounted within said cylinder and adapted to form a vacuum within the cylinder to move the diaphragm in one 80 direction, and means for returning the diaphragm to its normal position independent of the action of the piston, as set forth.

2. A pulp screening apparatus comprising a frame, a stock receptacle, a screen mounted 85 therein, a diaphragm mounted beneath said screen, an apertured pneumatic cylinder communicating with the space underneath said diaphragm, and a power piston mounted in said cylinder, and affording means whereby an unbalanced atmospheric pressure may 90 be brought to bear upon the diaphragm to vibrate the same, as set forth.

3. A pulp screening apparatus comprising a frame, a stock receptacle with a screen 95 therein, a diaphragm mounted within said receptacle, a spring bearing against the diaphragm, an apertured pneumatic cylinder communicating with the space below the diaphragm, a power piston mounted in said cylinder, and means for reciprocating said cylinder and adapted to cause an unbalanced atmospheric pressure to vibrate the diaphragm, as set forth.

4. A pulp screening apparatus comprising 105 a frame, a stock receptacle with a screen therein, a diaphragm mounted in said receptacle, an apertured pneumatic cylinder communicating with the space underneath said diaphragm, a spring bearing yieldingly against 110 the diaphragm, a power piston in said cylinder, an eccentric actuated pitman connected to said piston, as set forth.

5. A pulp screening apparatus comprising a frame, a stock receptacle with a screen 115 therein, a diaphragm mounted in said receptacle, an apertured pneumatic cylinder communicating with the space underneath said diaphragm, a spring bearing yieldingly against the diaphragm, a power piston in said cylinder, 120 an eccentric actuated pitman connected to said piston, and a valve regulated relief port communicating between said cylinder and the atmosphere, as set forth.

6. A pulp screening apparatus comprising 125 a stock receptacle, a screen therein, a diaphragm in said receptacle, an apertured cylinder communicating with the space underneath the diaphragm, a power piston mounted in said cylinder and independent of the dia- 130

- phragm, and means for reciprocating said piston, as set forth.
7. A pulp screening apparatus comprising a stock receptacle with a screen therein, a diaphragm mounted in said receptacle, an apertured pneumatic cylinder with a passage-way leading into the space underneath said diaphragm, a spring mounted within said space, and bearing yieldingly against the diaphragm, a power piston in said cylinder, an eccentric operated pitman connected with said piston, and a valve regulated relief port leading from the cylinder to the diaphragm, as set forth.
- 15 8. A pulp screening apparatus comprising a stock receptacle, a screen therein, with a delivery box having ports communicating between the same and said receptacle, a flow box communicating with said delivery box, a screen plate in the receptacle a diaphragm, a spring bearing yieldingly against the diaphragm, an apertured pneumatic cylinder communicating with the space under the said diaphragm, a power piston in said cylinder, an eccentric operated pitman connected to said piston, as set forth.
- 20 9. A pulp screening apparatus comprising a stock receptacle with a screen therein, a diaphragm mounted within the receptacle, a hollow casting fitted to the screen receptacle, a spring mounted in said casting and bearing yieldingly against the diaphragm, an apertured pneumatic cylinder fastened to said casting and communicating therewith, a power piston in said cylinder, a driving shaft, an eccentric thereon, a pitman actuated by said eccentric and pivotally connected to said piston, as set forth.
- 25 10. A pulp screening apparatus comprising a stock receptacle with a screen plate 40 therein, a diaphragm in the receptacle, a plate secured to said diaphragm, a boss projecting from said plate, a spring mounted about said boss and bearing against said plate, an apertured pneumatic cylinder 45 communicated with the space immediately below said diaphragm, a valve regulated relief port communicating between said cylinder and the atmosphere, a power piston mounted in said cylinder, and means for operating 50 the latter, as set forth.
11. A pulp screening apparatus comprising a stock receptacle with suitable delivery and flow boxes, a screen in said receptacle, a diaphragm, a plate secured to said diaphragm, 55 a boss projecting from said plate, a hollow casting fixed to said receptacle, a shell mounted in said casting, and in which said boss has a reciprocating movement, a spring about said boss, and shell, and bearing 60 against said diaphragm, an apertured pneumatic cylinder communicating, with the space immediately below the diaphragm, through said casting, a valve regulated relief port communicating between the said 65 cylinder and the atmosphere, a power piston in said cylinder, and means for operating the same, as set forth.

In testimony whereof I hereunto affix my signature in the presence of two witnesses. 70
